UNITED STATES PATENT OFFICE.

HARRY A. HOUGHTON, OF SEVILLE, OHIO.

BOAT-RAISING DEVICE.

1,240,453.

Specification of Letters Patent. Patented Sept. 18, 1917.

Application filed December 27, 1915. Serial No. 68,871.

To all whom it may concern:

Be it known that I, HARRY A. HOUGHTON, a citizen of the United States, residing at Seville, in the county of Medina and State of Ohio, have invented a certain new and useful Boat-Raising Device, of which the following is a specification.

The object of my invention is to provide a means for facilitating the raising of boats 10 out of the water for the purpose of draining or cleansing same, or making repairs to same, with reference more particularly to the smaller types of boats used at pleasure resorts. Attention is directed to the fact that 15 ordinarily it is necessary to drain such boats after each rain, and that when rains are frequent and where many boats are used, considerable labor is necessary. My invention greatly reduces this labor.

At the present time, in order to raise a 20 boat out of the water and place it upon a pier, it is customary for two or more persons to raise one end and drag the boat about half its length upon the edge of the pier, and 25 then, with the latter serving as a fulcrum and the boat as a lever, the other end is raised level with the pier and the boat dragged thereon to a position of safety. By 30 this method it is obvious that the boats are subjected to much wear and tear, and that in using a boat as a lever to raise its far or 35 lower end, it is subjected to severe strains, and even injurious strains when the lower end is weighted with considerable water, as is frequently the case, and leaky boats are bound to result.

The use of my invention effects various economies and conveniences, such as requiring but one person for its operation, the 40 position of a boat when raised facilitating interior cleansing, ease in raising and lowering, and absence of wear and tear; thus prolonging the lives of the boats.

One form of construction embodying the 45 principles of my invention is shown in the accompanying drawings, in which Figure 1 is a side elevation of the device, and Fig. 2 is a perspective view of the frame or lever. Broadly, the invention comprises a frame 50 (3) constructed of ordinary galvanized iron pipe and having two upright portions (3^a and 3^b), see Fig. 2; connected at the top by a bridge portion (3^c), and formed at the bottom with foot portions (3^d and 3^e) projecting therefrom at approximately right angles in such manner as to engage the keel

of a boat, as shown. To provide for varying heights of the water line, the upright portions are adjustably secured—by means of set screws or other clamping arrangement—60 to one part of hinges 4, the other part (4^a) being bolted to the pier. A pin (5) is secured to the frame at a point near the upper edge of the boat, for the purpose of preventing accidental displacement of the latter, 65 relative to the frame, when the latter is being raised out of the water. In some cases it is advisable that this pin be adjustably secured to the frame in order to accommodate boats of various heights. In order to 70 hold the boat in its elevated position, a hook (6) or other locking arrangement, to engage the upper portion of the frame, is provided.

In operation, with the frame in its upright position, a boat is moved centrally over the 75 foot portions and its near side depressed slightly to bring it under the pin 5, this being sufficient to prevent the boat floating out of position; the operator then grasps the upper end of the frame and swings it downwardly through an arc of approximately 90 degrees and then secures it by means of the hook 6; by reason of the frame acting as a 80 lever and the hinged connection at the edge of the pier serving as a fulcrum, the boat is raised without excessive exertion on the part of the operator, and to the position shown by the dotted lines, in which position the boat is quickly drained of water, and can be easily cleansed if necessary. The boat 85 is returned to the water by the operator releasing the hook and retarding the motion of the frame. Where heavier boats are to be handled, I lengthen that portion of the frame extending above the hinges and thus obtain greater leverage; in such cases a rope 90 is secured to the upper end of the frame in order to bring it within reach of the hand.

What I claim as my invention is:

1. In a device of the character described, 100 a lever-acting frame, a supporting means for same, a hinged connection between the frame and the supporting means, a portion of the frame extending below the hinged connection and adapted to engage a boat, and adjusting means associated with the hinged connection and the frame whereby 105 the boat-engaging portion of the latter may be positioned farther from or closer to the hinged connection.

2. In a boat tilting device of the character described, the combination of a support, a 110

lever fulcrumed thereto at a point above the water surface to one side of the center of its longitudinal extent, and thereby presenting a lever with a long arm and a short arm, 5 the long arm being adapted to receive the application of power, and the short arm having a submerged boat engaging position

adapted to extend below the bottom of a floating boat.

HARRY A. HOUGHTON.
